UNITED STATES PATENT OFFICE.

JOSEPH BERGER, JR., OF UTICA, NEW YORK, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,321,502.

Specification of Letters Patent. Patented Nov. 11, 1919.

Application filed December 30, 1916. Serial No. 139,821.

To all whom it may concern:

Be it known that I, JOSEPH BERGER, JR., a citizen of the United States, residing at Utica, in the county of Oneida, State of New York, have invented certain new and useful Improvements in Presser-Feet for Sewing-Machines, of which the following is a description, reference being had to the accompanying drawing and to the figures 10 of reference marked thereon.

The invention relates to new and useful improvements in a presser foot for sewing machines, and more particularly to a presser foot which is adapted to guide and overlap 15 the edges of fabric sections whereby the same may be united to form a flat seam.

An object of the invention is to provide a presser foot which is so constructed as to receive the up-turned edges of fabric sections 20 whereby they may be trimmed and prepared for overlapping and uniting, after which said presser foot operates to return the up-turned trimmed portions of the fabric sections to the plane of the fabric sections in 25 overlapped relation to each other.

A further object of the invention is to provide a presser foot of the above character with means for positively supporting one of the up-turned edges and means for 30 positively crowding the other up-turned edge underneath the first-named up-turned edge portion, after which said edge portions are brought into flat overlapped relation.

A still further object of the invention is 35 to provide a presser foot of the above character which is formed of two sections arranged side by side, and one of which is yieldingly mounted relative to the other so that the sections of fabric having the cross 40 seam therein may be joined to another fabric section.

These and other objects will in part be obvious and will in part be hereinafter more fully disclosed.

45 In the drawings, which show by way of illustration one embodiment of the invention:—

Figure 1 is a perspective view of a part 50 of a sewing machine having the improved presser foot applied thereto;

Fig. 2 is a top plan view of the same;

Fig. 3 is a top plan view of the work support, the throat plate and the feed dog, and also showing the needles;

Fig. 4 is a plan view of the improved 55 presser foot;

Fig. 5 is a perspective view of the same;

Fig. 6 is a perspective view of the auxiliary yielding section of the presser foot;

Fig. 7 is a detail in perspective showing 60 the front end of the main section of the presser foot;

Fig. 8 is a transverse sectional view 65 through the presser foot on the line 8—8 of Fig. 5;

Fig. 9 is a transverse sectional view on the line 9—9 of Fig. 5;

Fig. 10 is a longitudinal sectional view on the line 10—10 of Fig. 5;

Fig. 11 is a sectional view on the line 70 11—11 of Fig. 6;

Fig. 12 is a perspective view showing the front portion of the foot, the needles, and two fabric sections passing beneath the foot;

Fig. 13 is an enlarged view of a portion 75 of the foot, partly in perspective and partly in section, and showing the fabric sections and the manner of overlapping the same;

Fig. 14 is a diagrammatic view showing 80 the relation of the fabric sections to each other and to the stitching threads.

My improved presser foot is especially adapted for use in the joining by stitching of overlapped fabric sections. The edge portions of the fabric sections to be joined 85 are turned out of the plane of the fabric sections, and these up-turned portions are placed side by side and directed into a slot in the presser foot. A trimming mechanism operating at the upper face of the presser foot trims the edge portions of the fabric sections. The presser foot and throat plate are provided with means which positively support one of the up-turned edges and with means for positively crowding the other up-turned edge portion underneath the first up-turned edge portion, after which the first-named edge portion is returned to the plane 90 of its fabric section, and thus the fabric sections are overlapped so that they can be presented to the stitching mechanism and joined by stitching which not only covers the trimmed edges but which penetrates the overlapped fabric sections. 95

Referring more in detail to the drawings:—

The improved presser foot consists of a supporting shank 1 which is adapted to be

attached to the presser bar 2. The foot portion of the presser foot is formed into two sections, the main section 3 being rigid with the shank 1, while the auxiliary section 4 is 5 yieldingly connected thereto. Said shank portion 1 is provided with spaced lugs 5 and 6 between which the shank 7 of the auxiliary section 4 slides. The main section 3 is provided with a needle opening 8 into which 10 extends a stitch tongue 9. The auxiliary and main sections of the foot are spaced at their forward ends to form a slot 10 which extends from the front end of the presser foot longitudinally thereof and in substantially a line to the needle opening to a point adjacent the needle opening. This slot is 15 adapted to receive the up-turned edges of the fabric sections which are to be trimmed and joined by stitching.

20 In Figs. 12 and 13 of the drawings, I have shown the presser foot as used in connection with the stitching of a collaret strip to a garment. The collaret strip is indicated at 8 and the body of the garment to 25 which it is attached is indicated at G. The edge portion g of the body garment is turned up as indicated in the drawings and led into the slot 10. The collaret strip has its edges s also turned up and led into the 30 slot, and these up-turned edges are trimmed by a trimming mechanism which includes a fixed trimming blade 11, preferably carried by the main section of the presser foot, and a movable trimming blade 12 mounted on an 35 arm 13 which may be vibrated in any well-known way. The presser foot holds the material to be stitched on the work support, indicated at 14 in the drawings.

The presser foot is provided with a 40 raised throat plate 15 which is formed with feed slots adapted to receive the feeding devices, indicated at 16. The throat plate is also provided with needle openings to receive the needles of the stitching mechanism, which are indicated at 17 and 18. Coöperating with the needles 17 and 18 is a 45 thread hook 19, and a fixed thread guide 20 through which a cross thread is guided, and this thread hook which is oscillated by suitable mechanism engages the cross thread 50 and forms a loop therein for the entrance of the needle 17 which is farthest from the fixed thread guide. Coöperating with the needles 17 and 18 below the work support 55 is preferably a single looper so that the needle threads will be joined by the looper thread beneath the material.

In Fig. 14 of the drawings, I have indicated more or less diagrammatically the 60 collaret strip at S', the body of the garment at G, the thread of the needle 17 at 17^a, the thread of the needle 18 at 18^a, the cross thread at 20^a, and the looper thread at 7. It will be noted that the collaret strip 65 slightly overlaps the body of the garment,

the needle thread 18^a penetrates the collaret strip only, and the needle thread 17^a penetrates the body of the garment only. The cross thread 20^a and the looper thread connecting the needle threads will join the collaret strip to the body of the garment, and these cross threads, together with the needle threads, cover the trimmed edges of the collaret strip and the trimmed edge of the body of the garment. 70

In order to facilitate the guiding of the fabric sections to the presser foot, the throat plate is provided with a vertically extending fin 21 which extends into the slot 10. This fin, however, is tapered toward its rear 80 end so as to permit the trimming blades to be moved freely over the same, and finally so as to vanish and permit the fabric sections to be overlapped.

The auxiliary section 4 of the presser 85 foot is provided with a projecting guide 22 which extends wholly into the slot 10, and this projecting guide serves to positively turn down the up-turned portion G of the body of the fabric, crowding the same underneath the edge portions s of the collaret strip. The edge portions s of the collaret strip are positively held raised by this guide until after they have passed the same. The main section of the presser foot directly in 90 front of the needle opening 8 is cut-away to form an arched section 23. This arched section serves to engage the edge portions s of the collaret strip and positively return the same to the plane of the collaret strip, as 95 clearly shown in Fig. 13 of the drawing. It will thus be noted that the presser foot is provided with means for positively crowding one of the up-turned edge portions underneath the other, after which the upper 100 edge portion is positively turned down onto the lower edge portion, thus overlapping the edge portions. These devices which return the trimmed edge portions to the plane of the fabric sections in overlapped 105 relation are disposed between the trimming mechanism and the needle opening in the presser foot which determines the stitching point so that, after the edges are trimmed, they are positively brought back into overlapped relation before they cross the opening in the presser foot and, therefore, before 110 they are brought to the stitching mechanism. 115

The main section of the presser foot is 120 formed with an adjustable section 24. This adjustable section 24 is provided with a shank 25 which slides in a groove in the upper face of the main section of the foot, and a screw 26, passing through a slot in 125 said shank 25, holds this section 24 in an adjusted position. The section 24 is adjusted laterally, and for the purpose of closing up the slot 10 when moving the section 24 nearer to or farther from the vertical 130

fin so as to leave just sufficient space for the free passage of the upturned portions of the fabric sections. It is obvious that my improved presser foot may operate upon two fabric sections, each of a single thickness, and this section 24 of the main portion of the foot may be shifted so as to leave just enough clearance space for the guidance of the section that is being up-turned and 10 trimmed.

The auxiliary section of the presser foot is formed of two parts. The front portion 4^a has a work engaging surface terminating at the rear end of the slot 10. The rear 15 section of the part 4^a overlaps the rear part 4^b of the presser foot, and screws 27 passing through slots 28 are adapted to hold the part 4^a in an adjusted position on the part 4^b. This permits the part 4^a to be shifted 20 laterally and moved toward or from the vertical fin 21. The purpose of shifting this part of the foot is the same as that above described in connection with the part 24. It will thus be seen that the width of 25 the part 10 may be adjusted to accord with the thickness of the fabric sections being stitched. The auxiliary section 4 of the presser foot is formed with a shank, as above noted, which slides between lugs 5 and 30 6, and this shank is held in place by a suitable cover plate 29 and a screw 30 passing through a slot 31 in the shank limits the downward movement of the auxiliary section of the presser foot. A spring 31^a normally forces said shank downwardly. The 35 purpose of this yielding section of the foot is to facilitate the stitching of fabric sections which have cross seams formed therein.

It is obvious that minor changes in the 40 details of construction and the arrangement of parts may be made without departing from the spirit of the invention as set forth in the appended claims.

Having thus described the invention, what 45 is claimed as new is:—

1. A presser foot for sewing machines including in combination, a foot portion having a needle opening and a slot in said foot portion extending longitudinally of the foot 50 portion from the front end of the presser foot to a point adjacent the needle opening and entirely through said foot in a vertical direction, whereby upturned edge portions of fabric sections may be guided into said slot and extend above the foot portion where they may be trimmed, said presser foot having means in front of the needle opening for positively returning the upturned trimmed portions of fabric sections to the plane of 55 fabric sections and in overlapped relation.

2. A presser foot for sewing machines including in combination, a foot portion having a needle opening and a slot in said foot portion extending longitudinally of the 65 presser foot and from the front end of the

presser foot to a point adjacent the needle opening, said slot being adapted to receive the up-turned edge portions of fabric sections means carried by the presser foot in advance of the needle opening for positively 70 returning said fabric sections to the plane of the fabrics and in overlapped relation to each other, and means whereby the width of the slot may be varied.

3. A presser foot for sewing machines including in combination, a foot portion having a needle opening and a slot in said foot portion extending longitudinally of the presser foot and from the front of the presser foot to a point adjacent the needle 75 opening, said slot extending vertically entirely through said presser foot, whereby up-turned edge portions of fabric sections may be guided by said slot and extend upwardly through said slot where they may be 80 trimmed, a guide carried by the presser foot and extending laterally into said slot, said guide being constructed and disposed so as to crowd one of the trimmed edge portions of the fabric sections underneath the other 85 90 whereby the upturned portions of the fabric sections are returned flat and unfolded to the plane of the fabric sections in overlapped relation.

4. A presser foot for sewing machines including in combination, a foot portion having a needle opening and a slot in said foot portion extending longitudinally of the presser foot and from the front of the presser foot to a point adjacent the needle 95 opening, said slot being adapted to receive up-turned edge portions of fabric sections, a guide carried by the presser foot and extending laterally into said slot, said guide being constructed and disposed so as to 100 crowd one of the trimmed edge portions of the fabric sections underneath the other, said presser foot at the rear end of said slot having an arched section adapted to engage the upper trimmed edge portion and positively return the same to the plane of its 105 fabric section and in overlapped relation to the other fabric section.

5. A presser foot for sewing machines including in combination, a foot portion comprising a main section and an auxiliary section, said main section having a needle opening therein, means for yieldingly supporting the auxiliary section on the main section, said main section and said auxiliary 115 section being spaced in front of the opening to form a slot extending from the front end of the presser foot to a point adjacent the needle opening, said slot being adapted to receive the up-turned edge portions of 120 fabric sections whereby they may be trimmed, said auxiliary section of the presser foot having a guide projecting laterally into said slot for crowding one of the 125 trimmed edge portions of the fabric sec- 130

tions underneath the other edge portion, said main foot portion having an arched section in the slot at the rear end thereof for positively returning the upper edge portion onto the other fabric section and in overlapped relation thereto.

6. A presser foot for sewing machines including in combination, a foot portion comprising a main section and an auxiliary section, said main section having a needle opening therein, means for yieldingly supporting the auxiliary section on the main section, said main section and said auxiliary section being spaced in front of the opening to form a slot extending from the front end of the presser foot to a point adjacent the needle opening, said slot being adapted to receive the up-turned edge portions of fabric sections whereby they may be trimmed, said auxiliary section of the presser foot having
- 10
- 15
- 20

a guide projecting laterally into said slot for crowding one of the trimmed edge portions of the fabric sections underneath the other edge portion, said main foot portion having an arched section in the slot at the rear end thereof for positively returning the upper edge portion onto the other fabric section and in overlapped relation thereto, said auxiliary section being formed in two parts, one of which is adjustable on the other for varying the width of the slot, and said main section having an adjustable part for varying the width of the slot.

In testimony whereof, I affix my signature, in the presence of two witnesses.

JOSEPH BERGER, JR.
